US00D355411S

United States Patent [19]

Sadigh-Behzadi

[11] Patent Number: Des. 355,411

[45] Date of Patent: ** Feb. 14, 1995

[54] INTEGRATED CIRCUIT ELECTRONIC PACKAGE

[75] Inventor: Amir-Akbar Sadigh-Behzadi, Van Nuys, Calif.

[73] Assignee: Cicon Components, Inc., Chatsworth, Calif.

[**] Term: 14 Years

[21] Appl. No.: 9,137

[22] Filed: Jun. 4, 1993

[52] U.S. Cl. D13/182

[58] Field of Search D13/147, 182; 439/55, 439/65, 68, 70, 72, 76; 361/752, 783, 820; 174/52.4

[57] CLAIM

The ornamental design for an integrated circuit electronic package, as shown and described.

DESCRIPTION

FIG. 1 is a left, front perspective view showing my new integrated circuit electronic package design as it is attached to an integrated circuit;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof which is a mirror image of the left side elevational view.

*Fig. 2**Fig. 3**Fig. 4**Fig. 5**Fig. 6*
